TIRE BOOT.

1,407,305.

Specification of Letters Patent. Patented Feb. 21, 1922.

Application filed June 5, 1919. Serial No. 301,874.

To all whom it may concern:

Be it known that I, EDGAR M. STEELL, a citizen of the United States, residing at Spokane, in Spokane County and State of Washington, have invented certain new and useful Improvements in Tire Boots, of which the following is a specification.

The present invention relates to an improved tire boot designed for use in connection with pneumatic wheel tires for closing a fracture or cut in the outer casing of the tire, the boot to be inserted between the fractured casing and the inner tube of the tire as usual.

The primary purpose and objective of the invention is the provision of a boot that will be effective in holding close the edges of a fractured casing, especially while pressure is being brought into the tire by inflation, so that the fractured tire, when repaired will have the edges of the fracture or cut, in close proximity and the boot will hold the parts permanently in this position, distributing the strain over the entire area of the boot so that no one portion of the boot will be subject to excessive strain or distortion. Where the boot is used in connection with a hole in the outer casing, provision is made so that the boot will bridge or be stretched taut over the hole and be prevented from bulging out into the hole, and this is accomplished by the utilization of numerous spurs distributed over the entire area of the boot in order that not only may the material of the casing be strengthened and reinforced in proximity to the hole therein, but the support accorded the boot at all points surrounding the hole or opening in the casing, prevents the boot being forced into the hole, or in other words prevents bulging of the boot in the hole. By holding the walls of the fracture or opening as described, the boot prevents the casing from bulging at the point of fracture and holds the casing to the same diameter and size.

Numerous other advantages will appear hereinafter as the invention is specifically described, and attention is called to the drawings wherein one specific form of the invention is illustrated, the parts being combined and arranged according to the best mode so far devised for the practical application of the principles of the invention.

Figure 1 is a view in side elevation of the

boot, in its normal position assumed when 55 in place in a tire.

Figure 2 is a transverse view of a tire of usual construction with the boot in place.

Figure 3 shows one of the headed spurs that are employed between the layers of the 60 boot.

In order that the invention may be readily understood I have utilized the usual form of pneumatic wheel tire including the inner tube 1 and the outer casing 2 having the side 65 walls 3 and flanges 4 retained in the rim or felly 5, the boot, as a whole being indicated by the numeral 6 and designed to be inserted between the outer casing and the inner tube of the tire in order to close a fractured open- 70 ing or a cut in the outer casing.

The boot is made up of a pair of flexible layers of fabric as 7 and 8 indicating the outer and inner layers respectively. These layers may be of canvas or other fabric and 75 are flexible and they are vulcanized or cemented together, and provide a flexible boot, adapted to conform to the shape or contour of the tire with which they are to be utilized.

Interspersed over the whole area of the 80 boot are numerous spurs 9 that project through the outer layer of the boot and are designed to enter the inner wall of the outer casing of the tire when the boot is used. Each of these spurs is fashioned with a broad flat 85 head 10 of sufficient thinness to be encased between the layers of the boot, yet of sufficient strength to form a rigid foundation for the spur, so that the latter will always stand in radial position to the boot. Thus the entire 90 area of the boot is provided with spurs, spaced the required distance apart, and provided with rigid and firm bases or heads so that when the flexible boot adapts itself to the contour of the tire to be mended, the 95 numerous spurs radiate in the proper directions from the circumferential axis of the tire as a center, and enter the casing of the tire as understood.

The heads of the spurs are cemented and 100 encased between the two layers of the boot, and to further firmly anchor the heads, they may be provided with openings 11 and peripheral lugs 12 so that the cement or vulcanizing material may pass through these 105 openings and form connections between the two layers of fabric, and the lugs 12 may form means for closer cementing of the lay-

ers about these lugs to hold the heads more firmly and rigidly between their layers or retaining fabrics. The flow of the cement through the openings in the head and around 5 the lugs on the periphery of the head, enhance the binding effect of the cement and fix the heads against displacement or tipping sidewise.

When a tire is to be mended, the adjoining 10 walls of the fractured tire are cleaned and allowed to lie in close contact due to the resiliency or elasticity of the casing material, and when the boot is applied, the fractured place is substantially closed by the elastic 15 strength of the casing. Now when the boot is made effective by the introduction of air pressure back of it in the tire, before the fractured walls can be separated by the pressure, the numerous spurs engage the inner 20 walls of the casing and hold the casing, and as the pressure increases the spurs are forced into the casing and the edges of the fracture are still held in their original closed position, due to the presence of the numerous spurs 25 surrounding on all sides the fracture. Thus the fracture is reinforced and held closed against the entrance of pebbles dirt etc. that would tear the casing and inner tube, and

furthermore the numerous spurs anchor their surrounding area of boot so that movement 30 of the fabric of the boot is prevented and friction thus eliminated. And as before stated the tire casing is maintained in its normal shape and size and undue or excessive strain upon a weak portion of the tire is 35 eliminated, for, as a matter of fact, the reinforcing effect of the boot renders the fracture portion of the tire as strong in resisting pressure as the unfractured part of the tire.

What I claim is—

The combination with a fractured tire casing, of a reinforcing boot conforming to the contour of the tire and comprising outer and inner layers of flexible material and an intermediate cementing medium, of a multiplicity of flat heads interspersed over the whole area between the layers and provided with openings and lugs as described to enhance the binding effect of the cement, and said heads provided with radiating spurs extending transversely through the outer layer of the boot and piercing the inner wall of the outer casing of the tire.

In testimony whereof I affix my signature.

EDGAR M. STEELL.
